UNITED STATES PATENT OFFICE.

DWIGHT S. COLE, OF GRAND RAPIDS, MICHIGAN.

AUTOMATIC VALVE FOR WATER HEATERS.

Application filed May 13, 1921. Serial No. 469,371.

My invention relates to an improved automatic valve mechanism for controlling the fuel supply to heaters, and more particularly to such units as form parts of automatic rapid water heaters, but not necessarily limited in application thereto. In such constructions it is provided that the fuel or heating means, usually gaseous, be turned on, to heat the water as it flows through the heater, and off, as the water ceases to flow therethrough, by automatic means actuated to turn on the heat as a faucet on the delivery line from the heater is opened to permit water to be discharged and to turn off the heat simultaneously with the closing of the outlet faucet and the stoppage of the flow of water through the heater, all in a manner well known in this art in recent years. My invention has for an object to provide a simple, durable, efficient and economically manufactured automatic valve unit for heaters of this character, which may be readily assembled with and installed in a suitably designed heater of the designated class, and which may readily have the moving elements thereof removed from and replaced in its casing with little effort by comparatively unskilled labor, and without disconnecting any pipes or the valve casing from its assemblage in the heater. Other objects of my invention are to provide a novel, simple, inexpensive and highly efficient automatic-adjusting means of producing leak-proof joints where movable elements of the valve mechanism extend through a wall of the valve casing; a simple and inexpensive mounting for the fuel-valve disk to enable same to automatically adjust itself to its seat, and a simple adjustable by-pass within the water chamber for purposes hereinafter specified.

For an understanding of the invention by which these ends, and many others not at this time specifically enumerated, are attained, reference is made to the following description, taken in connection with the accompanying drawings, in which,

Fig. 1 is a front elevation of the unit of my invention.

Fig. 2 is an under view of the same.

Fig. 3 is an end elevation looking at the left hand end of Fig. 1.

Fig. 4 is a longitudinal vertical section taken substantially centrally of the unit.

Fig. 5 is a horizontal section taken on the

plane of line 5—5 of Fig. 4, certain parts of the mechanism being moved to a different position from that shown in Fig. 4, and

Fig. 6 is a transverse vertical section on the plane of line 6—6, of Fig. 4.

Like reference characters refer to like parts in the different figures of the drawings, and the sections shown in Figs. 5 and 6 are taken looking in the directions indicated by the corresponding arrows on the section lines.

As disclosed by the drawings, my new automatic valve is unique in its class and manner of installation in such heaters in that it is designed to be mounted within the casing of the heater and upon the base thereof to which it is secured in such manner that its main gas outlet connects with a cord passage in said base leading to nipples therein which direct streams of gas upward into mixing tubes suspended thereover and depending from the superimposed main burner of the heater. The water and gas supplies to the heater enter the casing of the automatic valve through vertical pipes which screw into suitably-threaded orifices, 16 and 31, in the bottom of its main casing, a suitable central orifice being provided through the base of the heater casing for the admission of said pipes and certain other parts of the valve structure therethrough. The water flows upward through its chambers in the casing and thence through a central rise-pipe to the top of the heating coils of the heater, and from said coils through pipes to service faucets where hot water is desired. Suitable orifices, 32 and 33, are provided in the tops of the gas chambers of the valve casing for supplying gas to the pilot lighting system of the heater, but as such pilot lighting system forms no part of the present invention same is not shown or described herewith.

Fig. 4 shows that the water and gas chambers of my improved automatic valve are disposed in opposite ends of one casting, which also serves to house certain elements of the movable parts by which the fuel is controlled. By uniting the said chambers in one casting the utmost certainty of accuracy in positioning the several elements of the valve mechanism is achieved and its consequent perfect action is attained and maintained in the highest possible degree.

The drawings disclose that the central portion of the valve casing consists essentially

of a vertical cylinder having openings in its interior wall adapted to the flow of fluid therethrough and to admit therein an arm extending from an adjoining chamber. Said cylinder terminates at its lower end at the common base of the casing, where it is closed by a suitable head, 10, and it extends upward, as indicated by numeral 7, above the other portions of the casing where it terminates in a flange, 7^a, adapted to having a connection made therewith. By making the bore of said cylinder of uniform diameter, and both of its ends open when cast, the accurate finishing of said bore is easily accomplished.

As clearly shown in Fig. 4, that portion of the casing at the left of said cylinder comprises two water chambers, one above the other, adapted to receive and direct water entering at inlet orifice 16 into the cylinder. The larger portion of said water passes to the cylinder through port 17 and the remainder through by-pass opening 24—25 and thence through the upper water chamber into the cylinder. The upper of said water chambers forms a housing for portions of the valve-operating mechanism hereinafter described. A recess or pocket 27, in the rear wall of the cylinder, cast integrally with the casing, provides a passage through which water flows past piston 18 when the heater is operating and delivering heated water. An outwardly-projecting hollow boss, 23, is provided at the left of said upper water chamber for the purpose of permitting the insertion and removal of arm 49 therethrough. Said boss contains an adjustable by-pass plug 22 screwed therein and is closed at its outer end by screw plug 26.

That portion of the casing to the right of said cylinder also comprises two chambers, separated by a perforated vertical partition, 28, adapted to admit the passage of a gaseous or fluid fuel therethrough, and in addition the outermost of said chambers forms a housing for the valve elements co-acting with the outer face of said partition surrounding said perforation therein to form a valve to control the flow of fuel from the inner to the outer of said gas or fuel chambers.

The valve mechanism is actuated to open the fuel valve by a piston, 18, fitted within the described vertical cylinder, said piston being forced upward by the pressure of the incoming water when the water flows freely through the heater, and is closed by a suitable spring, 55, external of the casing and suitably connected to the valve-operating mechanism, as hereinafter described, assisted by the weight of the piston elements acting downward upon arm 49 and thence through said valve-operating mechanism, when the flow of water through the valve and heater

The valve-operating mechanism embodies two rock-shafts, 34 and 34^a, horizontally mounted crosswise in the main casing; an arm 49 rigidly secured to rock-shaft 34^a and having its other end operably connected to piston 18 in the cylinder; a valve-disk-carrying arm 35 secured at one of its ends to rock-shaft 34 by screw 36; a valve disk 39 carried by arm 35; dependent arms 51 and 51^a rigidly secured to the externally-projecting ends of the said rock-shafts; a link, 54, hinged to and connecting the lower ends of said dependent arms, and a tension spring, 55, connected at one of its ends to the upper portion of dependent arm 51^a and at its other end to link 54 near to where it connects to the lower end of dependent arm 51, as clearly shown by the drawings.

Piston 18 is solid and close-fitting in the cylinder to prevent much leakage, when in its lower position, between its circumferential wall and the inner wall of the cylinder in which it reciprocates vertically. To insure that piston 18 shall at all times move true and not become cramped in the cylinder a guide piston, 19, of the same diameter as piston 18, is provided in the upper part of the cylinder, the two pistons being rigidly connected by a tie-bar, 20, cast integrally with both pistons. Vertical perforations, 21, are provided through piston 19 to permit of the free flow of all of the water passing to the heater therethrough without affecting the position of said piston. Both pistons are machined so as to leave all edges sharp to act as scrapers to clean off any particles of dirt which may lodge against the inner wall of the cylinder within their limits of travel, thus preventing such dirt from getting between the sliding surfaces and affecting the free movement of the pistons element. Tie-bar 20 has a suitable perforation, 50, to receive the end of arm 49 therethrough. Said perforation is made somewhat larger than the end of arm 49 to insure that it shall not interfere with the free movement of the pistons, and also to permit the pistons element to rotate slightly to add to its freedom of movement in the cylinder.

The by-pass 24—25 between the lower and upper water chambers is adjustable for the purpose of regulating the quantity of water which can be drawn through the heater without operating the valve mechanism to turn on the heating fluid to the main burner of the heater. The object of such regulation is to insure that a sufficient amount of water will be flowing through the heater, when the heating fluid is turned on to the burner thereof, to prevent steam from forming in the heating coils and at the same time to permit of delivering water at nearly the boiling point when desired. As normals of water pressure and heating fluid vary considerably at different places where such heat-

ers are to be installed it often becomes necessary to adjust the by-pass after the heater is installed to satisfy the normal conditions of said pressures at the places of installation. To this end perforation 25, through partition 8, is made larger than required to meet the conditions where a minimum of normal water pressure is found, and the quantity of water by-passed is regulated by 5 slightly turning by-pass plug 22 in either direction so that more or less of notch 24 in the side thereof is over perforation 25. As such adjustment is generally made finally when the heater is first installed the means 10 provided serve well to attain the desired end, are simple in construction and adjustment, and so placed that children or other meddlers cannot disturb the adjustment. A transfer of water from the lower to the upper water chamber in the casing must occur 15 when piston 18 descends and the gas valve closes. The more quickly such transfer occurs the quicker piston 18 will descend and the gas valve be closed. A simple nonadjustable perforation through partition 8 or 20 piston 18 would permit such transfer of water and such a plain perforation is all that would be necessary were it not for the need of regulating the flow through the heater, as 25 above described.

The removal and replacement of head 10, which closes the lower end of the cylinder, may occasionally be necessary for cleaning the interior of the cylinder or for repairs. 30 The form of said head and the means of securing same to the casing have been designed to that end, and a novice with a common screw driver can perform these operations easily and effectively, as the construction 35 clearly shows. The bottom of the casing is recessed about the lower end of the cylinder to receive a gasket, 11, therein. Head 10 is provided on its inner face with an annular collar which passes upward 40 through gasket 11 and a short distance beyond into the bore of the cylinder, which it fits closely. Said head extends laterally beyond said collar portion to cover the lower 45 face of said gasket and bears upward against the same. A downwardly-projecting ball-ended short boss is provided at the center of the bottom face of head 10 and is preferably formed integrally therewith. A bar, 50 12, extends diametrically across and beneath said head and contacts on its upper face with the tip of the rounded boss on said head. Both ends of said bar extend beyond said head and perforations to receive the bodies of screws are provided in the bar near its 55 ends. Screws 13 pass through said perforations from below and screw into threaded 60 perforations provided in ears 14 projecting from and forming extensions of the base of the casing, whereby when said screws are 65 made up firmly said bar will press said head

snugly against said gasket and thus make the joint between said head and the base of the casing leak-proof against the pressure of the water from within the casing. By this construction the upward pressure of bar 70 12 upon head 10 is always at the center of said head and thus exerts an equalized pressure upon all portions of said gasket. The above-described construction of the closing 75 of the lower end of the cylinder satisfies the requirements of practice in a very complete and satisfactory manner. Additional similar ears, 14^a, having internally screw-threaded perforations therethrough, are provided as side extensions of the base of 80 the valve casing to receive screws which secure said casing accurately and firmly in place on the base of the heater casing.

Many earlier inventors have attempted to design so-called "proportional-flow" valve mechanisms, to deliver varying quantities of water at a desired constant temperature, through such simple type of (not thermostatically controlled) heaters. Since the pressure and temperature of the water, and 85 pressure and quality of the gas, are all variables, as received from street service mains, it is not possible to achieve the results sought by any such "proportional-flow" devices. The most practical solution of the 90 problems involved by these variables is that in which the fire or heat is maintained as nearly constant as possible, while heated water is being delivered, and govern the temperature of the water being delivered by 95 varying the quantity discharged by opening the delivery faucet more or less—the larger the stream the lower the temperature and vice-versa. Moreover, gas burners do not 100 ignite satisfactorily or give efficient results when supplied with but a small part of their normal quantity of gas. These and other considerations have caused me to design my improved automatic valve mechanism so that 105 the gas supply to the burners of the heater is fully turned on or off by a very small variance in the quantity of water being drawn from the heater. To that end the lower margin of recess 27, provided in the rear 110 wall of the cylinder when the casing is cast, is located at such a height that the travel of piston 18 from its lowest position, as indicated by dotted lines 18^a in Fig. 4, to that 115 when it begins to uncover the lower margin of recess 27 will suffice to open the gas valve in the outer gas chamber of the casing sufficiently to permit of practically the full flow of gas to the burners of the heater. Any further rise of piston 18, as a larger quantity of water is being drawn, simply swings 120 the valve disk 39 farther from valve seat 29 without materially increasing the flow of gas to the burners of the heater.

In the construction of such automatic valves, as designed by many earlier inven-

tors, wherein the movements of a piston, actuated in one direction by hydraulic pressure to open the gas valve and a suitable spring closes such gas valve and forces the piston back to its original position, a piston rod or shaft has generally been employed between such piston and gas valve. Where such piston rod or shaft passes through the wall of the water chamber and again where it enters the gas chamber adjustable stuffing boxes containing some suitable packing material under more or less compression are employed to prevent leakage from such chambers outward. Where the water pressure encountered is high such packings must be made up quite tight to prevent leakage. In such cases the inward radial pressure of the packings upon the piston rod or shaft is so great as to frequently prevent the valve from being closed by the spring employed, thus leaving the gas turned on after the water has stopped flowing through the heater, with very disastrous results to the heater. To avoid such troubles I have devised a mechanism for the opening and closing of the gas valve in my improved automatic valve unit wherein a non-adjustable and highly efficient packing-means, producing a minimum of frictional resistance, is employed. To permit of the use of my improved packing-means in a simple and efficient manner I employ a novel construction of valve-operating mechanism, as shown by the drawings and as will now be explained.

The most distinctive feature of my new valve-operating mechanism consists in the employment of two rock-shafts, 34 and 34^a, which lie horizontally crosswise of and are inserted into the casing through orifices provided therefor in the front wall 1 of the casing. Bearings are provided for the rear ends of said shafts by bores made from the interior or front of the casing and extending from the inner face of the rear wall 3 of the casing nearly to the back ends of bosses 43 and 43^a, formed integrally with and projecting rearwardly from said back wall 3 of the casing. Said rock-shafts each have enlargements within the casing for the securing thereto of arms hereinafter described. Said enlargements, in their forward portions, constitute annular shoulders, 46 and 46^a, having at their front ends accurately and very smoothly finished flat surfaces in planes at right angles to the axes of the respective shafts, said smoothly faced surfaces extending from the outer margin of said annular shoulders inward to those portions of said shafts which extend forward through front bearings, provided as hereinafter described, and beyond said bearings for the rigid securing thereto of dependent arms, 51 and 51^a, at their respective front ends, as clearly shown by the drawings. The said orifices in the front

wall of the casing are provided with internal screw threads, and those portions of the front face of the casing surrounding said orifices are made flat in planes at right angles to the axes of said orifices. Glands, 47 and 47^a, are provided to close said orifices and the axial bores through said glands provide the front bearings, above referred to, for said rock-shafts. Said glands are exteriorly screw threaded for a portion of their lengths and such portions engage the interior screw threads of said orifices when said glands are in place. To facilitate the insertion into and removal of said glands from said orifices in the casing, and to insure that leakage shall not occur through said screw threaded joints, the outer portions of said glands are provided with heads which are larger in diameter than said screw threaded portions thereof. Said heads are preferably formed on their outer peripheries for the engagement of a wrench thereon, the rear faces of the heads being accurately faced to engage the above-described flat surfaces on the front face of the casing surrounding said orifices so as to form leak-proof joints therebetween when the glands are firmly screwed in place. The extreme inner ends of said glands have rectangular annular recesses machined therein to receive the larger portions of ring packings, 48 and 48^a, therein, said packings being preferably made of suitable leather saturated with a good water-proof lubricant and are firmly forced into said annular recesses with a die and press, so that the projecting portions of said ring packings shall be left smooth and in planes at right angles to the axes of the bores through said glands. To prevent inward radial expansion of the said ring packings the annular recesses in the ends of said glands are so formed as to leave collars of the metal of the glands between the inner diameters of said ring packings and the axial bores through said glands, the free ends of said collars being made flush with the end faces of the glands outside of said packings. The said collars prevent said packings from binding upon the circumferential walls or surfaces of the bearing portions of the rock-shafts which pass through said glands—all as shown clearly in Fig. 5. The exposed faces of said ring packings form the surfaces upon which the above-described smooth annular flat surfaces, provided at the front ends of the shoulders of the enlarged portions of the rock-shafts, contact and oscillate as the valve mechanism operates in service, and when adequate pressures are applied to hold the said contacting surfaces together the joints made by them are leak-proof against all pressures met with in such installations. The oscillating movements of the rock-shafts tend to improve said joints and the packings

prove very efficient and durable in practice. As the pressure of gas supplies from common street service mains is very slight I have provided an additional force axially to 5 rock-shaft 34 to hold its smooth radial shoulder 46 against ring packing 48 to prevent gas leakage therebetween. To this end an axial bore is made in the rear end of rock-shaft 34 to an adequate depth, a suitable compression spring 45 is placed in the 10 inner portion of said bore and a free-fitting plunger 44 in the outer portion of said bore, said plunger bearing at its inner end against said spring and having its outer end projecting from the rock-shaft and terminating in a point which bears pivotally against the end of the bore in boss 43, previously described, thus producing an inexpensive and practically frictionless constant forward 15 thrust on said rock-shaft, for the specified purpose. As the water pressure within the water chambers of the casing tends constantly to expel rock-shaft 34^a from the casing no other force is required to hold the 20 contact between the packing surfaces provided for said rock-shaft constantly leak-tight. The tightness of said packing joint is automatically varied as the water pressure in the water chambers varies, the joint 25 being tighter as the pressure increases and the tendency for leakage increases, and vice-versa. Usage for a considerable period has demonstrated that the packing-means described are excellent solutions of the problems involved from every point of view, and at the same time they are exceedingly simple and economical to produce.

As hereinbefore stated, an arm 49 is provided to transfer motion from piston 18 to 30 rock-shaft 34^a. Said arm has one of its ends rigidly secured to said rock-shaft and its other end projects through perforation 50 in tie-bar 20 which rigidly connects solid actuating piston 18 and perforated guide piston 19 to form a single unit or element. Said arm 49 is preferably made in the form 35 of a special screw having a suitable notched head at its secured end, a screw-threaded portion adjoining said head, and a plain cylindrical extension of smaller diameter than said threaded portion forming its other end. Rock-shaft 34^a has a screw-threaded axially-transverse perforation in its enlarged central portion, with a flat surface surrounding 40 and at right angles to the axis of said perforation to form a seat for the said head on arm 49. The screw-threaded portion of arm 49 is made of such a length that the head on said arm will project somewhat from the 45 hollow boss 23 of the casing after said threads have begun to engage the threads in the transverse perforations in said rock-shaft, said provision of long-threaded portion being made to facilitate the removal of arm 49 from rock-shaft 34^a and thence from 50 the casing by the use of a simple screw driver engaging the notch in the head of said arm. The construction of arm 49, above described, and its assemblage in the valve train are clearly shown in Figs. 4, 5 70 and 6.

The enlarged central portion of rock-shaft 34 within the outer gas chamber of the casing has one end of valve-disk-carrying arm 35 secured thereto by screw 36, as clearly 75 shown in Fig. 4. The other end of arm 35 has a conical perforation formed therethrough, the larger end of said perforation being toward the interior of the casing. An annular plate 38, has a perforated spherical 80 hollow boss formed integrally with its central portion, the outer surface of said boss being adapted to fit into the described conical perforation in arm 35. A valve disk, 39, of oil-saturated leather or other suitable 85 material, bears with one of its faces against the flat portion of the inward face of plate 38, being co-axial therewith, and is held thereagainst by a combined plate and nut, 40, said part 40 having a notched head projecting 90 from one face thereof and an internally screw-threaded cylindrical portion projecting from its other face—said last-described portion passing through an axial perforation in valve disk 39 and thence into the 95 recessed portion of plate 38. A screw 37, having a compression spring 41 under its head, passes axially through a small washer and thence through the conical perforation 100 in arm 35 and the perforation in plate 38 and screws into the internally screw-threaded portion of part 40, thus holding 105 the several parts together securely and somewhat flexibly upon arm 35, as shown in Fig. 4. The construction described produces a 110 mounting for valve disk 39 whereby same is firmly pressed and held against valve seat 29, surrounding orifice 28^a in partition 28, when the valve is closed, and said disk will automatically shift sufficiently when necessary 115 to adapt itself to its seat regardless of slight inaccuracies of construction incident to the economical production of such parts.

In practice valve disk 39 and parts which mount same on arm 35 are assembled on said arm and then such assemblage is introduced into the casing through an opening provided for that purpose in the end 4 of the casing, screw 36 being then put in place to secure arm 35 to rock-shaft 34, said screw being 120 readily accessible through said opening when the valve disk is against its seat. A plug-cap 42, best shown in Fig. 4, serves to close said opening in the casing against gas 125 leakage.

Dependent arms 51 and 51^a are secured to the forward ends of rock-shafts 34 and 34^a respectively by special screws, 52 and 52^a, as indicated in Figs. 1 and 3 and disclosed more fully in Fig. 6 by the dotted lines in 130

dicating the outlines of the concealed portions of said screws. As indicated in Fig. 6, said screws are special in that tenon-like cylindrical portions of same project beyond the disk and its assemblage may be removed 5 threaded portions thereof to form the ends from the casing and replaced therein with of said screws opposite their heads. Said tenon-like ends fit snugly into holes accurately positioned and drilled radially to a suitable depth into the end portions of the rock-shafts, said holes being clearly indicated in Fig. 5, which construction serves to lock said arms securely in correct angular positions on their respective shafts. The described means for securing arms 51 and 51^a in place serve as combined locating keys and securing means, thus satisfying all such requirements in a very simple and inexpensive manner.

The lower ends of arms 51 and 51^a have forwardly-projecting pins, 53 and 53^a, formed integrally therewith, said pins having transverse perforations therethrough, as shown in Fig. 6, to receive cotter pins, 54, shown in Figs. 1 and 2. A simple link, 54, having transverse perforations near its ends, is correspondingly turned through the lever and engaging pins 53 and 53^a, and being secured thereto by said cotter pins, serves to connect the lower ends of said arms by hinged joints, thus causing said arms to function together in opening and closing the fuel valve device in the casing. A suitable tension spring, 55, is connected at one of its ends to an ear formed integrally with the upper portion of arm 51^a, and at its other end to an ear formed integrally with link 54 near that one of its ends which connects to pin 53, as shown in Fig. 1. When the faucet or tap is closed, the pressure above and below the piston 18 is greater than that above it sufficient to overcome the spring 55. When the faucet or tap is opened, the pressure above and below the piston 18 promptly equalizes and the spring 55 draws the parts back to closing position, bringing the piston 18 below the difference of pressure in the lower and upper water chambers of the casing to lift piston 18 from its lowest position in the cylinder.

In assembling the valve mechanism in the casing the procedure is very simple and is as follows, viz: (a) Insert rock-shafts 34 (having spring 45 and plunger 44 therein) and 34^a and secure them with glands 47 and 47^a having ring packings 48 and 48^a inset therein. (b) Secure dependent arms 51 and 51^a to their respective projecting ends of the rock-shafts with screws 52 and 52^a. (c) Assemble and secure the gas-valve-disk 39 and its mountings on arm 35, and said arm to rock-shaft 34 by screw 36, and then put closure 42 in place. (d) Insert the pistons-element 18—19—20 in cylinder, and arm 49 through boss 23, rock-shaft 34^a and perforation 50, followed by by-pass plug 22 and closing plug 26. (e) Secure cylinder head 10 in place. (f) Place link 54 on pins 53 and 53^a and secure same thereon with cotter pins, as shown. (g) Put spring 55 in place, and the assemblage is complete. Obviously the dismantling of the parts may be accom-

plished in the reverse order to that of assembling.

In this connection it is to be noted that either the pistons-element or gas-valve-

lindrical portions of same project beyond the disk and its assemblage may be removed

without disturbing the other or any pipes that connect to the valve casing, or any of the moving parts of the mechanism at the front

of the casing, and also without removing the rock-shafts, the rock-shafts or glands

which retain same in the casing. These glands

lock said arms securely in correct angular positions on their respective shafts. The de-

scribed means for securing arms 51 and 51^a after the heater has been in service for a

considerable period.

From the foregoing it is clear that when a faucet or tap in the system is opened in

full, the pressure of the water against the

under side of piston 18 elevates it to the position shown in Fig. 4 so that the water

can run freely by the piston through the passage at 27. This elevation of the piston

shown in Fig. 6, to receive cotter pins, as shown in Figs. 1 and 2. A simple link, 54, turning shaft 34^a, whereupon shaft 34 is cor-

respondingly turned through the lever and link bar connections between the shafts and

thereon by said cotter pins, serves to connect the lower ends of said arms by hinged joints, thus causing said arms to function together in opening and closing the fuel valve device in the casing. A suitable tension spring, 55, is connected at one of its ends to an ear formed integrally with the upper portion of arm 51^a, and at its other end to an ear formed integrally with link 54 near that one of its ends which connects to pin 53, as shown in Fig. 1. When the faucet or

tap is closed, the pressure above and below the piston 18 is greater than that above it sufficient to overcome the spring 55. When the faucet or

tap is opened, the pressure above and below the piston 18 promptly equalizes and the spring 55 draws the parts back to closing

position, bringing the piston 18 below the difference of pressure in the lower and upper water chambers of the casing to lift piston 18 from its lowest position in the cylinder.

In assembling the valve mechanism in the casing the procedure is very simple and is as follows, viz: (a) Insert rock-shafts 34 (having

spring 45 and plunger 44 therein) and 34^a and secure them with glands 47 and 47^a having ring packings 48 and 48^a inset therein. (b) Secure dependent arms 51 and 51^a to their respective projecting ends of the rock-shafts with screws 52 and 52^a. (c) Assemble and secure the gas-valve-disk 39 and its mountings on arm 35, and said arm to rock-shaft 34 by screw 36, and then put closure 42 in place. (d) Insert the pistons-element 18—19—20 in cylinder, and arm 49 through boss 23, rock-shaft 34^a and perforation 50, followed by by-pass plug 22 and closing plug 26. (e) Secure cylinder head 10 in place. (f) Place link 54 on pins 53 and 53^a and secure same thereon with cotter pins, as shown. (g) Put spring 55 in place, and the assemblage is complete. Obviously the dismantling of the parts may be accom-

plished in the reverse order to that of assembling.

In this connection it is to be noted that either the pistons-element or gas-valve-

lindrical portions of same project beyond the disk and its assemblage may be removed

without disturbing the other or any pipes that connect to the valve casing, or any of the moving parts of the mechanism at the front

of the casing, and also without removing the rock-shafts, the rock-shafts or glands

which retain same in the casing. These glands

lock said arms securely in correct angular positions on their respective shafts. The de-

scribed means for securing arms 51 and 51^a after the heater has been in service for a

considerable period.

the replacement of the packings makes the joints as good as new for another long period of service. Access to the mechanisms carried by said shafts is easy, in fact, every part of the construction is designed with particular reference to facility in construction, assembly, repair if needed, and adjustment so as to make a substantially perfect unit for the purposes desired, and at low cost of manufacture.

In practice, this construction has proved its merit over a considerable length of time of continuous use. The appended claims define the invention and I consider myself entitled to all forms of structure which come within the scope thereof.

I claim:

1. A construction of the class described comprising a hollow casing provided with a vertical cylinder between its ends and with water receiving upper and lower chambers at one side of the cylinder communicating with each other and with the vertical cylinder, and gaseous fuel chambers at the other side of the cylinder, a piston in the cylinder adapted in lower position to stop the passage of water and in an upper position to permit free passage of water by it from the lower water chamber, movable valve means disposed between the fuel chambers in closed position stopping passage of fuel from one chamber to the other, means for mounting the valve means, and means operatively interposed between the piston and said valve means mounting for opening or closing the valve means as the piston is raised or lowered, substantially as described.

2. A device of the class described comprising a hollow integral casting formed between its ends with a vertical cylinder open at both ends, a plate closing the lower end of the cylinder, said upper end of the cylinder being adapted for connection to a water system, said casing at one side of the cylinder being divided into upper and lower compartments both in communication with each other and the cylinder, a piston mounted in the cylinder, said cylinder above the lower position of the piston having a lateral enlargement to form a passage by the piston when it is elevated, the casing at the other side of the cylinder being divided vertically into two chambers by a vertical partition having an opening therethrough, a closing valve for said opening mounted movably in one of said chambers, and means for operating said valve from open to closed position, or vice versa, by movement of the piston, the lower of the first mentioned compartments being adapted to receive water under pressure, and one of said chambers being adapted to receive gaseous fuel under pressure and the other having an outlet through which it may escape, substantially as described.

3. A device of the class described, compris-

ing a hollow unitary casing having compartments into which water and gaseous fuel under pressure may be received, and also a vertical cylinder disposed between the water and the fuel compartments, the water compartments communicating with each other and said cylinder, a piston in the cylinder, means normally holding the piston in a lower position when the pressure on opposite sides of the piston is substantially equalized, said

piston being elevated by pressure of water when the pressure above the piston is relieved, a lateral passage in the side of the cylinder communicating with the cylinder on opposite sides of the piston for the passage of water by the piston when elevated to upper position, a valve closing the fuel receiving compartment against escape of fuel when the piston is in lower position, and means for opening the valve actuated by the piston on its elevation, substantially as described.

4. In a construction of the class described having a casing with compartments into which fluids under pressure may be entered, of shafts mounted in said compartments, each of said shafts having an enlarged central portion and an annular shoulder at the juncture of one end of the shaft with its central portion, a nut threaded into the side of the casing for each shaft, the shafts passing through said nuts, a groove in the inner face of each nut spaced from the bore thereof, a ring packing inset in each groove and pressing against the shoulder of each shaft, and means for rotatably supporting the opposite ends of the shaft in the opposite side of the casing.

5. In a construction of the class described, a hollow casing formed as an integral casting with spaced apart sides, ends, bottom and top, a cylindrical neck open at its upper end extending upwardly from the casing between its ends, said casing between its upper and lower sides having walls continuing the neck to form a vertical cylinder, a horizontal partition between one side of the cylinder and an end of the casing dividing the casing at such side of the cylinder into upper and lower compartments, each of said compartments having communication with the cylinder, and said horizontal partition having a relatively small opening therethrough connecting the compartments, a piston mounted in the cylinder for vertical movements, said

cylinder a distance above the normal lower position of the piston having a lateral enlargement, a vertical partition dividing the casing at the other side of the cylinder into two chambers, said partition having an opening therethrough, a valve movably mounted in one of said chambers adapted to close the opening, means operated by the piston, and means operatively connected with said means operated by the piston for actuating the

valve to open or closed position, said lower compartment at one side of the cylinder being adapted to receive water under pressure, and one of said chambers at the opposite side of the cylinder being adapted to receive gaseous fuel under pressure, the other chamber having an outlet for the escape thereof, substantially as described.

6. In a construction of the class described, 10 a hollow casing formed as a unitary casting formed with a vertical cylinder between its ends, upper and lower compartments at one side of the cylinder, each of which has communication with the cylinder, and two separated chambers at the opposite side of the cylinder with a connecting opening between them, an opening of relatively small size connecting the said compartments, a horizontal shaft rotatably mounted in one of 20 said chambers, an arm secured thereto, a valve attached to the free end of the arm adapted to close said opening between the chambers, a second shaft horizontally mounted across the upper compartment, an 25 arm extending therefrom into the cylinder, a piston in the cylinder, means connecting the arm on said second shaft to the piston, the cylinder above the normal lower position of the piston having a lateral enlargement, each of said shafts extending through 30 a side of the casing, an arm attached to the outer end of each of said shafts, a link connecting the arms, and a spring connected at one end to the link adjacent its point of connection to one arm and at its other end to the other arm above the pivotal axis of the shaft to which it is connected, the lowermost compartment being designed to receive water under pressure, and the chamber in which 35 the first shaft is not mounted being designed to receive gaseous fuel under pressure, said chamber in which the first shaft is mounted having an outlet therefor, substantially as described.

7. A construction containing the elements in combination defined in claim 4, combined with an interiorly bored boss on the opposite side of the casing to receive the opposite end of the shaft, said opposite end of 50 the shaft being bored lengthwise from and at said end, a spring seated in the opening in the shaft, and a pointed plug loosely positioned in the opening in the shaft and extending beyond the end of the shaft to bear under pressure from the spring against the bottom of the opening in said boss, substantially as described.

8. In a construction of the class described, 55 a casing having a vertical cylinder formed

with a lateral enlargement at one side and two compartments located one over the other and separated by a partition positioned at one side of the cylinder and both communicating therewith, said lower compartment being adapted to receive water under pressure, and said upper compartment being connected with the lower compartment by a passage of relatively small size through the partition, means for regulating the flow of water from the lower to the upper compartment, a piston in the cylinder adapted to move between a lower and an upper position in the first of which it is below said lateral enlargement to the cylinder and in the latter of which it is at such enlargement, a 65 gaseous fuel passage control, and means for operating the same by movements of the piston, opening the same when the piston is moved to upper position and closing the same when the piston is moved to lower 70 position.

9. In a construction of the class described, a casing including a vertical cylinder formed with a lateral enlargement at one side and with two compartments located one 75 over the other and separated by a partition located at one side of the cylinder, both of the compartments communicating with the cylinder, said lower compartment having an opening through its lower side and said upper compartment having an interiorly threaded opening at its outer end, a plug inserted in said threaded opening and having a longitudinal recess cut longitudinally in one side, said partition between the compartments having an opening of relatively small size therethrough communicating with the recess, means permitting rotation of the plug to vary the flow of water to the cylinder, a closure for the opening at its outer 80 end, a piston in the cylinder, a shaft rotatably mounted across the upper compartment, and a connection between the shaft and said piston, substantially as described.

10. In a construction of the class described, a casing including a vertical cylinder and a lateral extension divided into upper and lower compartments communicating with the cylinder and with each other, fuel compartments and a valve for controlling the flow of fuel between the compartments, a piston in the cylinder, means for operating the piston and fuel valve simultaneously, part of the said operating means being housed in the upper compartment.

In testimony whereof I affix my signature.

DWIGHT S. COLE.
